UNITED STATES PATENT OFFICE.

EDMUND H. LUNKEN, OF CINCINNATI, OHIO.

SCREENING DEVICE FOR POCKET-WINDOWS.

1,259,114.

Specification of Letters Patent. Patented Mar. 12, 1918.

Application filed March 9, 1917. Serial No. 153,708.

To all whom it may concern:

Be it known that I, EDMUND H. LUNKEN, a citizen of the United States, and a resident of Cincinnati, in the county of Hamilton and 5 State of Ohio, have invented certain new and useful improvements in Screening Devices for Pocket-Windows, of which the following is a full, clear, and exact description, reference being had to the accompanying 10 drawings, forming part of this specification.

My invention relates to screens for windows having a wall pocket to receive all of the sashes, of the type wherein the screens are adapted also to pass into the pocket.

15 In devices of this character there are many difficulties in structurally arranging the screens, the sash and the pocket so that there are no unprotected openings left for access of dust when the windows are closed, in providing mounting means for the screens which permits of easy removal for repairs and adjustment, and also in providing for proper adjustment of the parts with relation to each other, so that a practical screen device will 20 be provided. Also there is necessity in this art for simplicity of construction so as to bring the obvious advantages of pocket windows and pocket screens within the range of standard practice in building construction, 25 such that they can be installed by the ordinary builder and carpenter.

It is the object of this invention to provide a simple practical screening device for pocket windows wherein the above difficulties are well done away with, and said object is accomplished by that certain construction and arrangement of parts to be hereinafter more specifically pointed out and claimed.

In the drawings,

40 Fig. 1 is a longitudinal section taken through a window, showing the complete device.

Fig. 2 is a perspective view of the screen channel member.

45 Fig. 3 is a horizontal sectional detail on the line 3, 3, of Fig. 1.

Fig. 4 is a detail perspective view of one of the lower corners of the window pocket, showing the screens in place and locked in 50 the pocket by the new catch of my invention.

Fig. 5 is a detail perspective view of a

section of the window stile, showing the adjustable mounting for the outer channel support.

Fig. 6 is a detail perspective section of one 55 of the screens.

The window is shown as having stiles 1, a sill 2 and a cap trim 3 and a wall pocket 4 located above the cap trim. The lower sash 5 and the upper sash 6 of the window are 60 adapted to pass entirely into the wall pocket and are provided with the new and useful pulley devices capable of insertion from the window opening shown and described in my Patent No. 1,201,598, dated October 17, 1916. 65

There is a parting strip 7 between the sashes, and on the inside of the window frame is the inner guide rail 8 which may or may not be laterally adjustable, as desired. The structure so far briefly described forms 70 no part of the invention herein except in combination with the various constructions to be described below.

The outer guide strip 9 of the window is of a length to extend clear up into the pocket 75 of the window and seat at the upper end in a socket 10 at the top of the pocket. The screen channel 11 is mounted on this guide rail and mountably removable with it.

For mounting the guide rail and channel 80 it is merely tipped up into the pocket with its upper end in the socket at the top thereof, and then screwed to the stile of the frame at various points in a manner to be described. The channel has a plug 11^a in the top to 85 make an easy fit in the socket. The guide rail might be screwed down in any usual manner, but it is preferred by me to have it adjustable laterally so as to take up inequalities in construction and make the fit of the 90 window sash tight and snug.

Accordingly the guide rail is cut with laterally widened slots 12 (Fig. 5) for the attaching screws 13, and the screen channel member is screwed to the stile by passing 95 the screws through these slots, thereby screwing down the guide rail at the same time. When it is desired to adjust the guide rail the screws may be loosened, the guide rail tapped over to the desired position and the 100 screws tightened down again.

For inserting the screens in the channel

member, which is double the width of the screen moldings, a section 14 thereof is cut out from the rest of the channel shortly above the meeting line of the screens when mounted, and is adapted to be removably mounted as an insert in the channel by screws 15.

There is a lower screen 16 and an upper screen 17, the lower screen being provided 16 with a removable extension molding piece 18 so as to interlock with the moldings of the upper screen when in place (Fig. 1). The upper screen is provided at its upper end with a molding extension piece 19, which is 15 the full size of the channel and slides in the channel, which is not the case with the lower screen extension piece.

The channel member is provided at its lower portion with a filler strip 20, which 20 runs from the bottom of the channel up to the point where it is desired to have the lower molding of the upper screen when the window screens are in place. This filler piece is the size of one of the screen moldings and therefore provides a snug half sized channel which will fit the molding of the lower screen, it being remembered that the channel is twice the size of the screen moldings as above stated.

30 It can be realized that this channel construction is very simple and compact and easily assembled. My application for patent Serial No. 148,030, filed February 12, 1917, shows a somewhat similar construction, and 35 this invention is considered by me as a species of the general screen channel idea expressed therein. The channel member in this instance is in one piece, however, and the filler member runs the length of the lower 40 screen, which is new in this application, as is the adjustable nature of the channel support and guide rail.

As in the said application, there is provided on the upper rail of the upper window 45 sash a molding 21, which retains in place a weather strip 22. The weather strip bears against the extension on the upper screen when the screens are down, and more important still bears against the lower molding of 50 the lower screen when the screens are in the pocket. However in this instance there are set in this molding 21, small ferrule like pieces 23 which are slotted for the attaching 55 screws 24. The screws may thus be employed to permit lateral adjustment of this molding so as to adjust somewhat the position of the weather strip or take up its wear.

60 Mounted on the outside trim 25 of the window, at the base of the pocket, are swinging catches 26 which can be swung into the path of the screens and thus hold them up in the wall pocket. The catches are the size of the screen channel and thus close up the space left by the channel when the lower

screen and upper screen are both up in the 65 pocket. When not in use the catches may be swung out of the way, as shown in dotted lines at —A— in Fig. 4. It should be noted that the channel pieces are provided with a slot 28 which permits the catch to swing into 70 position to hold the screens, and which support the catch when the screens are above it. The catch when in use puts practically no strain on its pivot.

For compensating for the weight of the 75 screens, they are provided with the usual springs 27 to slide in the channel, and tend frictionally to hold the screens against movement. In other ways the device shown in the drawings is similar to that of my application above referred to, which need not be described, since they form no part of this invention.

Having thus described my invention, what 80 I claim as new and desire to secure by Letters Patent, is:—

1. In a pocket window, the combination of a sliding sash in the window adapted to slide into the pocket thereof, an outer guide rail for the window extending into the 90 pocket, a screen channel member mounted on the guide rail and extending into the pocket, and means for adjustably mounting said guide rail, for the purpose described.

2. In a pocket window, the combination of a sliding sash in the window and adapted to slide into the pocket, an outer guide rail mounted in the window and extending into the pocket, a screen channel member mounted on the guide rail and extending through 100 its entire length, and means for adjustably mounting said guide rail comprising screws in the channel member, and slots registering therewith in the guide rail, said screws 105 adapted to engage in the window.

3. In a pocket window, a screen guiding and retaining element for a plurality of screens, comprising channel members extending the length of the window on both 110 sides for receiving said screens, said channel members being double the width of the screen moldings, and a filler piece inserted in the channel at the lower end thereof to narrow the channel to half size for the lower 115 screen and exclude the upper screen therefrom.

4. In a pocket window, a side guide for a plurality of screens comprising a channel of double the screen molding width and of a 120 length to extend along the window opening and the wall pocket of said window, and means for excluding the upper screen from the lower portion of the said channel member.

5. In a pocket window of the character described, screen members, channel members adapted to retain and guide said screen members, same being adapted to permit 125

movement into the pocket of said window, and a catch adapted to swing into the channels and hold the screens up in the pocket.

6. In a pocket window of the character described, screen members, channel members adapted to retain and guide said screen members, same being adapted to permit

movement into the pocket of said window, and a catch adapted to swing into the channels and hold the screens up in the pocket, 10 said channel having a slot in the wall thereof to receive and support the catch.

EDMUND H. LUNKEN.
